CLAIM

I claim the ornamental design for a toggle paddle for a rear view device, as shown and described.

DESCRIPTION

FIG. 1 is a rear top perspective view of one embodiment of a toggle paddle for a rear view device of the present disclosure;

FIG. 2 is a rear bottom perspective view of the toggle paddle for a rear view device of FIG. 1;

FIG. 3 is a front elevational view of the toggle paddle for a rear view device of FIG. 1;

FIG. 4 is a rear elevational view of the toggle paddle for a rear view device of FIG. 1;

FIG. 5 is a top plan view of the toggle paddle for a rear view device of FIG. 1;

FIG. 6 is a bottom plan view of the toggle paddle for a rear view device of FIG. 1;

FIG. 7 is a side elevational view of the toggle paddle for a rear view device of FIG. 1;

FIG. 8 is a rear top perspective view of another embodiment of a toggle paddle for a rear view device of the present disclosure;

FIG. 9 is a rear bottom perspective view of the toggle paddle for a rear view device of FIG. 8;

FIG. 10 is a front elevational view of the toggle paddle for a rear view device of FIG. 8;

FIG. 11 is a rear elevational view of the toggle paddle for a rear view device of FIG. 8;

FIG. 12 is a top plan view of the toggle paddle for a rear view device of FIG. 8;

FIG. 13 is a bottom plan view of the toggle paddle for a rear view device of FIG. 8; and,

FIG. 14 is a side elevational view of the toggle paddle for a rear view device of FIG. 8.

The broken line showing of the rear view device is provided for purposes of environment and forms no part of the claimed design. The portions of the second embodiment depicted by broken lines form no part of the claimed design.
